UNITED STATES PATENT OFFICE.

ERNEST B. FLETCHER, OF TORONTO, ONTARIO, CANADA, ASSIGNOR TO FLETCHER MANUFACTURING CO. LIMITED, OF TORONTO, CANADA.

BREAD PAN.

Application filed December 18, 1924. Serial No. 756,761.

To all whom it may concern:

Be it known that I, ERNEST B. FLETCHER, of the city of Toronto, in the county of York, Province of Ontario, Canada, a subject of the King of Great Britain, have invented certain new and useful Improvements in Bread Pans, of which the following is a specification.

This invention relates particularly to bread pans of which a plurality are connected to straps or frames by means of brackets, and my object is to provide means for strengthening and stiffening these brackets and for rigidly connecting them to the pans.

I attain my objects by means of the constructions hereinafter described and illustrated in the accompanying drawings in which

Fig. 1 is an end view of a pair of pans showing my improved bracket attached thereto and ready to receive the frame member;

Fig. 2 a plan view of the underside of the same;

Fig. 3 a cross section on the line 3—3 in Fig. 1;

Fig. 4 a plan view of the bracket;

Fig. 5 an end elevation of the same; and

Fig. 6 a side elevation of the same.

In the drawings like numerals of reference indicate corresponding parts in the different figures.

The bread pans 1 are provided with beaded ends 2 and beaded sides 3, which are formed by providing each pan with a wire 4 over which the edges of its ends and sides are rolled.

Heretofore a plurality of these pans have been secured together by means of brackets secured to adjacent sides of adjacent pans, at opposite ends thereof, and by pan connecting straps 6 secured at 7 to the remote sides of the end pans and at 11 to the brackets. These straps extend along the opposite ends of the pans.

The brackets are provided with longitudinal flanges 8 adapted to be secured in the wired sides 3 of adjacent pans. This is accomplished by passing the flanges 8 between the wires 4 and the rolled edges of the sides of the adjacent pans so that the flanges are rolled round the wires, see Fig. 1. The brackets are provided with grooves forming

ribs 9 adapted to receive portions of the beaded sides 3 and to strengthen the brackets. Each bracket has a depending portion 10 formed thereon and adapted to lie against and be riveted at 11 to the strap 6.

With the above arrangement the pans have too much side sway relative to one another due to the weak construction of the brackets.

In Figs. 4, 5 and 6 is shown my improved bracket which is provided with the hereinbefore mentioned flanges 8, ribs 9 and a depending portion 10. To stiffen the latter I form one or more ribs 12 therein. These brackets are formed of sheet metal stamped to shape and bent to form the portions 10. The ribs 12 are formed by extending the ribs 9 past the bend in the bracket, so that the ribs will also be formed in the portion 10. The portion 10 of each bracket is also provided with extensions or tabs 13 adapted to be rolled in the wired ends 2 of adjacent pans in a similar manner to the rolling in of the flanges 8. These tabs are formed by slitting the flanges 8 adjacent the bend in the brackets as indicated at 15. To further stiffen the device the metal of the brackets is displaced at 14 to fit into indentations formed in the beaded sides 3. This is accomplished by punching the brackets at the back of the grooves after the flanges and tabs are secured in position.

The method of securing together a plurality of pans 1 is as follows. The tabs 13 and flanges 8 of the brackets are inserted between the wires 4 and the rolled edges at 90 adjacent corners of a pair of pans and then the bracket is driven or pressed until the flanges and tabs are rolled round the wires. Any number of pans may thus be secured together and it will be readily seen that the tabs 13 will prevent lateral movement of one pan relative to the other and that the ribs 12 will greatly strengthen the portions 10 which are secured by the rivets 11 to the pan connecting straps 6. These straps are then secured to the pans at the ends thereof and the metal of the brackets displaced at 14 as hereinbefore described.

What I claim is:—

1. The combination with a pan having wired edges formed on its sides and ends, of a bracket having flanges rolled into the said wired edges along the adjacent sides

of two adjacent pans and provided with tabs rolled into the said wired edges on the ends of the adjacent pans.

2. A bracket having a pair of spaced flanges, each flange being adapted to be rolled into a wired edge of a pan and having a depending portion adapted to be connected to a pan connecting strap, the said portion having a strengthening rib stamped therein.

3. A bracket having a pair of spaced grooves and flanges tangential to the walls of the said grooves, each of the latter being adapted to be rolled into a wired edge of a pan; a depending portion for connection with a pan connecting strap formed on the bracket; and stiffening ribs formed in the depending portion by extending the said grooves into the depending portion.

4. A bracket having a pair of spaced flanges, each flange being adapted to be rolled into a wired edge of one side of a rectangular pan and having tabs, each tab being adapted to be rolled into a wired edge on another side of the said pan.

5. A bracket having a pair of spaced flanges, each flange being adapted to be rolled into a wired edge of one side of a rectangular pan and having a depending portion for connection with a pan connecting strap; and tabs formed on the depending portion, each tab being adapted to be rolled into a wired edge of a side of the said pan adjacent to the first mentioned side.

6. A bracket adapted to be secured to adjacent sides of a pair of pans and having

longitudinal stiffening ribs formed therein, the bracket being bent to form a depending portion adapted to be secured to a pan connecting strap; and strengthening ribs 40 formed in the depending portion by extending the first mentioned ribs past the bend in the bracket.

7. A bracket having a pair of spaced grooves and flanges tangential to the walls 45 of the said grooves, each of the latter being adapted to be rolled into a wired edge of a pan; a depending portion formed on the bracket for connection with a pan connecting strap; and stiffening ribs formed in 50 the depending portion by extending the said grooves into the depending portion, the depending portion being formed by bending the bracket intermediate its ends and being provided with tabs formed by slitting 55 the flanges adjacent the said bend, the tabs being adapted to be rolled into another wired edge of a pan.

8. The combination with a plurality of 60 pans having wired sides and ends; and pan connecting straps secured to the end pans and extending past the ends of the other pans, of brackets having flanges rolled into the adjacent wired sides of the pans and provided with depending portions secured 65 to the said straps, the depending portions being provided with tabs rolled into the wired ends of adjacent pans.

Signed at Toronto this 27th day of November 1924.

ERNEST B. FLETCHER.
